UNITED STATES PATENT OFFICE.

PERCY I. ANSORGE, OF BROOKLYN, NEW YORK.

DESIGN FOR A LIGHTING-FIXTURE PART.

Application filed August 8, 1922. Serial No. 3,327. Term of patent 7 years.

To all whom it may concern:

Be it known that I, PERCY I. ANSORGE, a citizen of the United States, residing at No. 787 E. 5th St., borough of Brooklyn, in the city of New York, county of Kings, and State of New York, have invented a new, original, and ornamental Design for Lighting-Fixture Parts, of which the following is a specification, reference being had to the accompanying drawing, forming part thereof.

Figure 1 is a plan view of my new design.

Figure 2 is a side view of my new design comprising ornamental center or body as shown from which arms or projections for the support of electric lights are attached as shown.

I claim:

The ornamental design for a lighting fixture part as shown and described.

PERCY I. ANSORGE.
